UNITED STATES PATENT OFFICE.

CLIFTON E. KOONCE, OF COALINGA, CALIFORNIA.

STEAM TURBINE.

Application filed September 17, 1921. Serial No. 501,242.

To all whom it may concern:

Be it known that I, CLIFTON E. KOONCE, a citizen of the United States, residing at Coalinga, in the county of Fresno and State 5 of California, have invented new and useful Improvements in Steam Turbines, of which the following is a specification.

This invention relates to improvements in steam turbines, the principal object of which 10 is to devise a turbine which is compact, one which may be reversed and one which is simple to construct.

Another object of this invention is to devise a turbine wherein there is a minimum 15 number of parts some of which can be readily replaced when necessary, and a turbine that will assure freedom from mechanical troubles incident to complicated machines.

Another object of this invention is to devise 20 a turbine of the character described, which will be very light and compact, with the result that the same may be used in automobiles and like road vehicles, and a turbine which can be readily assembled and 25 disassembled.

Other objects and advantages will be apparent during the course of the following description.

In the accompanying drawings forming a 30 part of this specification and in which like numerals are employed to designate like parts throughout the same,

Fig. 1 is an end elevation of my device.

Fig. 2 is a side elevation of Figure 1.

35 Fig. 3 is a detail view of the valve chamber.

Fig. 4 is a cross-section, taken on the line 4-4 of Figure 5.

40 Fig. 5 is a cross-section taken on the line 5-5 of Figure 4.

Fig. 6 is a cross-section taken on the line 6-6 of Figure 4.

Figures 7 and 8 comprise a fragmentary detail view of the ports.

45 In the accompanying drawings wherein for the purpose of illustration is shown a preferred embodiment of my invention, the numeral 5 designates a base having supports 6 and 7 mounted thereon. These supports

50 serve to support the turbine as a whole. The numerals 8 and 9 refer to two semi-circular castings closed at their ends, and forming a cylindrical housing for the rotors. These castings 8 and 9 are suitably secured

55 together as by bolts 10, and are provided

with bearings for a shaft 11 centrally disposed therein. This shaft 11 has keyed thereto rotors 12, 13 and 14, which rotors are each provided with a series of buckets about their periphery, said buckets being 60 angularly disposed with respect to the center line of said rotors, the buckets upon one side of the rotor continuing the same angle as the buckets on the opposite side.

Division members 15 and 16 are disposed 65 between the rotors and end plates 17 and 18, and are adapted to abut the outer surface of the end rotors. These division members and end plates are adapted to control the direction that steam is admitted to the 70 rotors through the medium of passages formed therein.

When the turbine is moving in a direction indicated by the arrow of Figure 4, steam is admitted to the steam chambers 75 19 and 20, and as the same are identical, but one will be described.

The steam chamber is formed by an elongated housing 20 bolted to the castings 8 and 9, and a slide valve 21 is provided 80 therein. This slide valve is operated in the usual manner by a rod 22, and needs no description.

Suitable ports are provided in said valve 85 so that steam entering through passage 23 may be controlled to the proper sides of the rotor.

Assuming now that steam is admitted to the chamber 19, the steam will pass as indicated by the rotors through ports 24 and 90 25 into the end plate 18 and division member 15. After entering the end plate 18, it will be diverted through the passage 26 to the right hand side of the rotor, as shown in Figure 5. The steam entering the 95 division member 15 will pass through passages 27 and 28 to the rotors 13 and 14. This steam will be effective through a quarter of the revolution, from which point the same will escape as through exhausts 29. 100 Steam entering the lower steam chamber of the turbine will follow in exactly the same course except that it will exhaust through an exhaust valve 30.

To reverse the engine, the slide valve 21 105 is moved to the left of the drawing, as shown in Figure 5, which will result in the steam entering the division member 16 through port 31 and end plate 17, through port 32. Steam will then be caused to travel 110

to the opposite sides of each of the rotors as will be noted by examining these ports, as shown in Figure 6.

It will thus be seen that I have constructed a turbine, which has the buckets angularly disposed with relation to the center line of the rotor, and that I control the direction in which the steam is admitted to the rotors by the simple manipulation of slide valves, the same resulting in steam being admitted to either one side or the opposite sides of the rotors to cause either forward or reverse movement thereof, all of the parts being simple to construct and consequently cheap to manufacture.

It is to be understood that the form of my invention herewith shown and described is to be taken as a preferred example of the same, and that various changes in the shape, size, and arrangement of parts may be resorted to without departing from the spirit

of the invention or the scope of the subjoined claim.

Having thus described my invention, I claim:

In a rotary turbine, the combination of castings, steam chambers formed on said castings, slide valves mounted in said steam chambers, ports in said slide valves, ports in said castings, a shaft carried by said castings, rotors placed on said shaft, division members between said rotors, ports in said division members, and buckets formed on said rotors, said buckets on the opposite sides of said rotors being in axial alignment when adapted to receive steam therein for the purpose of causing rotation of said rotors in either a forward or reverse direction.

In testimony whereof I affix my signature.

CLIFTON E. KOONCE.
